UNITED STATES PATENT OFFICE

94,089

DESIGN FOR A CHAIR SEAT

Walter Clyde Lucas, Asheboro, N. C., assignor to
National Chair Company, Inc., Asheboro, N. C.,
a corporation of North Carolina

Application September 12, 1934, Serial No. 53,268

Term of patent 14 years

To all whom it may concern:

Be it known that I, Walter C. Lucas, a citizen of the United States, residing at Asheboro, county of Randolph, State of North Carolina, have invented a new, original, and ornamental Design for a Chair Seat, of which the following is a specification, reference being had to the accompanying drawing, forming a part thereof.

Figure 1 is a perspective view of the chair seat of my invention.

Figure 2 is a view in top plan of the seat of my invention.

Figure 3 is a view in side elevation of the chair seat.

I claim:

The ornamental design for a chair seat as shown.

WALTER CLYDE LUCAS.
